(57) **CLAIM**

The ornamental design for a trash cabinet as shown and described.

DESCRIPTION

FIG. 1 is a front elevational view of a trash cabinet showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front, right perspective view thereof;

FIG. 8 is a bottom, front, right perspective view thereof;

FIG. 9 is a top, rear, right perspective view thereof; and,

FIG. 10 is a top, front, left perspective view of the trash cabinet where the trash cabinet is in an open state.

The broken lines in the drawings depict portions of the trash cabinet that form no part of the claimed design.
